UNITED STATES PATENT OFFICE.

FRITZ HUSCHLER, OF JERSEY HEIGHTS, NEW JERSEY.

DESIGN FOR A PHONOGRAPH TONE-ARM.

• 57,344.

Specification for Design.

Patented Mar. 15, 1921.

Application filed October 7, 1920. Serial No. 415,461. Term of patent 7 years.

To all whom it may concern:

Be it known that I, FRITZ HUSCHLER, a citizen of Germany, and a resident of Jersey Heights, in the county of Hudson and State of New Jersey, have invented a new, original, and ornamental Design for a Phonograph Tone-Arm, of which the following is a specification, reference being had to the accompanying drawing, forming part thereof.

The figure is a front view of a phonograph tone arm showing my new design.

I claim—

The ornamental design for a phonograph tone arm as shown.

FRITZ HUSCHLER.
